(57) **CLAIM**

The ornamental design for a lighter holder, as shown and described.

DESCRIPTION

FIG. 1 is a perspective view of a lighter holder showing my new design;

FIG. 2 is a front view of the lighter holder shown in FIG. 1; FIG. 3 is a rear view of the lighter holder shown in FIG. 1; FIG. 4 is a left side view of the lighter holder shown in FIG. 1;

FIG. 5 is a right side view of the lighter holder shown in FIG. 1;

FIG. 6 is a top view of the lighter holder shown in FIG. 1; and,

FIG. 7 is a bottom view of the lighter holder shown in FIG. 1.

The broken lines shown in the drawings depict portions of the lighter holder that form no part of the claimed design.
